UNITED STATES PATENT OFFICE.

FREDERICK L. McGAHAN, OF ST. LOUIS, MISSOURI.

SMELTING-FURNACE.

No. 834,747.

Specification of Letters Patent.

Patented Oct. 30, 1906.

Application filed June 28, 1905. Serial No. 267,399.

To all whom it may concern:

Be it known that I, FREDERICK L. McGAHAN, a citizen of the United States, residing at the city of St. Louis, State of Missouri, have invented a certain new and useful Smelting-Furnace, of which the following is such a full, clear, and exact description as will enable any one skilled in the art to which it appertains to make and use the same, reference being had to the accompanying drawings, forming part of this specification.

The object of my invention is to provide a smelting-furnace in which the heated products of combustion and unconsumed gases are withdrawn from the furnace and after being passed through a carbureter to enrich them are again returned to the furnace, so that not only is the heat utilized, but also any unconsumed gases are consumed in their second passage through the furnace.

Another object of my invention is to draw the said heated products of combustion and gases over fresh ore, so that the said ore is roasted preliminary to being smelted in the smelting-furnace proper.

The construction of my smelting-furnace, briefly stated, is as follows: I provide a pair of smelting-chambers, preferably cylindrical and upright in form. Each of these smelting-chambers is provided with a plurality of combustion-chambers opening laterally into the said smelting-chambers, each combustion-chamber being provided with a fuel-injector for injecting fuel in order to heat the main or smelting chambers. Leading from each smelting-chamber is also an inclined inclosure divided by a grating into a roasting-chamber and a circulating-chamber. The two inclined inclosures are connected at their upper ends, and at this point is attached a pipe through which the heated products of combustion and gases are drawn off over the ore in the roasting-chamber by means of a suction-fan. The said gases and products of combustion are then delivered to a carbureter, in which they are enriched by the addition of any suitable fuel, either liquid or pulverized, after which the said gases and products of combustion are again returned to the smelter proper by means of a second suction-fan. After being returned to the furnace proper the gases are first passed through superheating-pipes arranged adjacent to the smelting-chamber and are then delivered to the various combustion-chambers hereinbefore referred to.

In the accompanying drawings, which illustrate one form of smelting-furnace made in accordance with my invention, Figure 1 is a top plan view of a complete smelting plant. Fig. 2 is a side elevation of the same. Fig. 3 is a central section, on an enlarged scale, through the smelter proper. Fig. 4 is an enlarged section on the section 4-4 of Fig. 6. Fig. 5 is a sectional view showing a detail of construction. Fig. 6 is a top plan view, partly in section, of the parts shown in Fig. 3; and Figs. 7 and 8 are vertical central sections through the carbureter, Fig. 8 being shown on a line at right angles to the section 7-7 of Fig. 7.

Like marks of reference refer to similar parts in the several views of the drawings.

10 represents the two smelting-chambers, which are preferably cylindrical and upright in form. Opening laterally off these smelting-chambers 10 are the combustion-chambers 11, which are preferably arranged at an angle of about forty-five degrees with the said main or smelting chambers 10. Each 80 of the combustion-chambers 11 is provided with a fuel-injector 12, which is provided with a supply of fuel and steam by pipe connections, which will be fully hereinafter described.

13 represents inclined inclosures, preferably arranged at an angle of about forty-five degrees. Each of these inclosures is divided by means of a grating of water-tubes 14 into an upper or roasting chamber 15 and a lower 90 or circulating chamber 16. The ends of the pipes 14 are secured in boxes 17, which in turn are connected, by means of pipes 18 and 19, with water-drums 20, arranged at each side of and slightly above the said inclined 95 inclosures 13. The roasting-chambers 15 are separated from the smelting-chambers 10 by means of sliding doors 21, each of which doors 21 is provided with a grating formed of water-tubes 22. The ends of these tubes 22 100 are connected to the tubes 18 by means of jointed tubes 23, so as to allow the doors 21 to be raised and lowered. The doors 21 are preferably raised and lowered by means of pneumatic or steam hoists 25, as shown in 105 Fig. 3. The upper end of each of the roasting-chambers 15 is provided with a swinging door 26, so that the upper end of the said chamber can be opened for the insertion of a charge of ore. Such a charge of ore is preferably inserted by means of a hopper 27, which is provided with a slide 28, and a telescoping 110

portion 29, which is adapted to be lowered into the position shown in Fig. 3, so that when the slide 28 is drawn the contents of the hopper 27 will be discharged into the roasting-chamber 15. Leading from the point of junction of the two circulating-chambers 16 is a pipe 32, through which the heated products of combustion and unconsumed gases are drawn off by means of a fan 33. These gases and products of combustion are then discharged into a carbureter 34, which is shown in detail in Figs. 7 and 8. The pipe 32, leading from the fan 33, has an enlarged end 35, which passes down through the carbureter 34 and is preferably slightly belled at the end, as shown at 36 in Figs. 7 and 8. Opening into the enlarged portion 35 is a second pipe 37, which leads from the smoke-stack of the boiler 38. A fan 39 is provided for drawing off the products of combustion and heated gases from the boiler 38 through the pipe 37 and discharging them into the lower enlarged end 35 of the pipe 32. Arranged below the flared or belled end 36 of the enlarged pipe 35 is a crucible 40. Arranged just above this crucible 40 is a perforated partition 41 and above said partition 41 a second imperforate partition 42. Passing through these two partitions 41 and 42 are a plurality of pipes 43, preferably made of two different lengths, as clearly shown in the drawings. These pipes are arranged annularly in close proximity to the outer shell of the carbureter 34, and their object is to allow the passage of oil or oil and water through the space separated by the partitions 41 and 42. Between the partitions 41 and 42 and closely surrounding the pipe 35 is the gas-generating chamber 45. Leading from this gas-generating chamber 45 are a pair of pipes 46, which are connected to a suction-fan 47. Leading from the fan 47 are a pair of pipes 48, which return the gases and heated products of combustion to the smelter proper, as will be hereinafter more fully described. Leading from the carbureter 34 below the crucible 40 are a pair of pipes 50, which are in turn connected to separating-tanks 51. Below each of the separating-tanks 51 is arranged a dead-oil tank 52, with which it is connected by means of pipes 53. Leading from the two dead-oil tanks 52 is a pipe 54, which is connected, by means of a pipe 55, with a pump 56. Leading from the pump 56 is a pipe 57, through which the dead oil from the tanks 52 is pumped into a reservoir 58.

59 is a return-pipe from the reservoir 58, through which the dead oil is returned to the carbureter 34. In order to prevent the carbureter from falling to too low a temperature, I prefer to provide it with a pair of burners 60. These burners 60 are each provided with an oil-pipe 61, by means of which the oil is supplied to the burner. These pipes 61 are connected to a pipe 62, which leads from a pipe

63, communicating with the fuel-oil tank 64. The pipe 62 is also connected with the burner 65 of the boiler 38. In order to heat the fuel-oil in the tank 64, I provide a steam-coil 66 in said tank. This coil 66 is supplied by steam from a pipe 67, which is connected by a pipe 68 with a pipe 69, in turn connected to the steam-drum 70 of the boiler 38. The pipe 67 is connected to the steam-cylinder of the pump 56, hereinbefore referred to, and also to the steam-cylinder of a second pump 72. The exhaust of the steam-cylinders from both the pump 56 and the pump 72 passes through a pipe 73 to the carbureter 34. The suction end of the pump-cylinder of the pump 72 is connected, by means of a pipe 74, with a retort 75, connected with the gas-generating chamber 45 of the carbureter 34, and the said suction end of the said cylinder is also connected, by means of a pipe 76, with a series of separating-chambers 77 in a passage 78, leading to a well 79. This passage 78 receives the discharge from a relief-pipe 80, extending from the pipe 32, and also from a relief-pipe 81, connected with the separating-tanks 51 and also with the pipe 37 through a pipe 82, also connected to the pipes 46. 83 is the discharge-pipe from the pump-cylinder of the pump 72. This pipe 83 may lead to any suitable receptacle for the various products withdrawn from the carbureter 34 and the separating-chambers 77.

The carbureter 34 also receives the exhaust from the heating-coil 66 in the fuel-oil tank 64. This exhaust passes from the coil 66 through a pipe 85, passing along within the pipe 63. Exhaust-steam is also supplied to the carbureter 34 through a pipe 86, leading from the engine 87. This engine 87 is used to drive the various exhaust-fans by means of suitable counter-shafting and belting, which are not shown in the drawings. The engine 87 is supplied with steam by means of the pipe 69, hereinbefore described. Leading from the steam-dome 70 of the boiler 38 is a pipe 87, which pipe is connected with a super-heating-coil 88^a, arranged in the smoke-box of the boiler, as clearly shown in Fig. 5 of the drawings. Connected with this coil 88^a is a pipe 89, which is in turn connected to the pipe connections 90, surrounding the two smelting-chambers 10. Leading from the pipe connections 90 to each of the fuel-injectors 12 is a branch-pipe connection 91. 92 represents oil-pipe connections, also surrounding the smelting-chambers 10. Leading from these oil-pipe connections 92 to each of the burners 12 is a branch pipe 93. The oil-pipe connections 92 are supplied by means of a pipe 94, Fig. 2, leading from the pipe 63, hereinbefore described. 95 represents superheating-pipes, which are arranged adjacent to the smelting-chambers 10. These superheating-pipes 95 are preferably four in number for each smelting-chamber, and they are arranged, as

clearly shown in the drawings, Fig. 6, so as to form a continuous passage, one end of each of said passages being connected to one of the pipes 48 leading from the carbureter, as hereinbefore described. The opposite end of each of the sets of passages formed by the superheating-pipes 95 is provided with a discharge-nozzle 96, as shown in Fig. 3. This discharge-nozzle 96 preferably discharges centrally in the upper part of the smelting-chamber 10. Leading from one end of each of the superheating-pipes 95 is a branch pipe 97, which leads into one of the combustion-chambers 11, so as to discharge the superheated gases into the said combustion-chamber. Leading into the opposite end of each of the said superheating-pipes 95 is a branch pipe 98, leading from the steam-pipe connections 90. The discharge-nozzle 96 is also preferably provided with a supply-pipe 99, leading from the oil-pipe connections 92. Arranged in this pipe 99 is a sight-feed lubricator 100, so that the amount of oil fed through the pipe can be readily observed. In order to supply pressure on the fuel in the fuel-tank 64, I connect to said tank an air-pipe 101, leading from an air-pump 102. This pump 102 is also connected with an air-tank 103, so that a supply of air may be retained on hand after the plant is shut down in order to readily start the plant into operation. Leading from the pump 102 and tank 103 are two pipes 104 and 105. The pipe 104 leads to the burner 65 of the boiler 38, hereinbefore described, and the pipe 105 leads to the pipe 89, connected to the steam-pipe connections 90, so that in starting up the plant, or, if desired, at any other time, compressed air may be used in the steam-pipe connections 90 in place of steam.

The operation of my smelting-furnace is as follows: When the plant is in full operation, each of the smelting-chambers 10 will be provided with a charge of ore, and this ore will be heated by means of the combustion-chambers 11, opening into the smelting-chamber 10. At the same time each of the roasting-chambers 15 will be provided with a second charge of ore, which is placed in the chamber 50 by means of the hopper 27, as has been hereinbefore described. The heated products of combustion and gases pass up through the water-grates 22 and into contact with the ore in the chambers 15, from whence they pass down through the water-grates 14 into the circulating-chambers 16, after which they are drawn through the pipe 32 by means of the fan 33 and discharged into the upper end of the carbureter 34. At the same time that the heated products of combustion and gases pass down through the pipe 32 into the enlarged pipe 35 gases from the furnace 38 will also be discharged into the said pipe 35 through the pipe 37 by means of the fan 39.

At the same time exhaust-steam and dead oil

will be discharged into the upper end of the carbureter outside of the pipe 35 through the pipes 85, 86, 59, and 73. The oil and water from these pipes will pass down through the pipes 43 and tend to maintain the carbureter 70 at the proper temperature. At the same time the dead oils and steam will be decomposed, forming gases, which are returned through the pipes 46 to the fan 47 and thence through the pipes 48 to the superheating-pipes 95 surrounding the smelting-chamber. After the gases have been thoroughly superheated in the pipes 95 they are returned through the branch pipes 97 to the combustion-chambers 11. As soon as the charge of ore within the smelting-chamber 10 has been smelted it can be drawn off through the usual discharge-openings 107, as shown in Fig. 3. A discharge-opening 108 may be also provided for the discharge of the slag from the smelting-chamber. After the slag and metal have been discharged from the smelting-chamber 10 the doors 22 are raised by means of the hoists 25, so that the charge of roasted ore from the roasting-chambers 15 may pass 90 into the smelting-chambers 10.

In addition to the liquid fuel fed to the carbureter 34 I may also provide a hopper 110, as shown in Figs. 2 and 8, for receiving pulverized fuel, which may be fed into the crucible 40 by means of a screw 111. Arranged, preferably, below the discharge 112 from the hopper 110 is a pipe 113, leading from the crucible 40 and provided with an opening 114. Through this opening the gas within the carbureter 34 can be tested to discover when it is of sufficient richness to enable it to be drawn off through the pipes 46 and supplied to the smelting-chambers.

Having fully described my invention, what I claim as new, and desire to secure by Letters Patent of the United States, is—

1. In a smelting-furnace, the combination with an ore-smelting chamber, of a combustion chamber or chambers for heating said ore-smelting chamber, means for withdrawing the heated products of combustion and unconsumed gases from said ore-smelting chamber and returning the same to said combustion chamber or chambers, superheating-pipes surrounding said ore-smelting chamber, to which superheating-pipes said products of combustion are delivered, and communications between said superheating-pipes and said combustion chamber or chambers. 110
2. In a smelting-furnace, the combination with an ore-smelting chamber, of a combustion chamber or chambers for heating said ore-smelting chamber, means for withdrawing the heated products of combustion 115 and unconsumed gases from said ore-smelting chamber and returning the same to said combustion chamber or chambers, superheating-pipes surrounding said ore-smelting chamber, to which superheating-pipes said products of combustion are delivered, and communications between said superheating-pipes and said combustion chamber or chambers. 120
3. In a smelting-furnace, the combination with an ore-smelting chamber, of a combustion chamber or chambers for heating said ore-smelting chamber, means for withdrawing the heated products of combustion 125 and unconsumed gases from said ore-smelting chamber and returning the same to said combustion chamber or chambers, superheating-pipes surrounding said ore-smelting chamber, to which superheating-pipes said products of combustion are delivered, and communications between said superheating-pipes and said combustion chamber or chambers. 130

- products of combustion are delivered, means for feeding steam to said superheating-pipes, and connections between said superheating-pipes and said combustion chamber or chambers.
3. In a smelting-furnace, the combination with an ore-smelting chamber, of a combustion chamber or chambers for heating said ore-smelting chamber, means for withdrawing the heated products of combustion and unconsumed gases from said ore-smelting chamber, a carbureter receiving said heated products of combustion and unconsumed gases, superheating-pipes adjacent to said ore-smelting chamber, means for returning said heated products of combustion and unconsumed gases from said carbureter to said superheating-pipes, and communications between said superheating-pipes and said combustion chamber or chambers.
4. In a smelting-furnace, the combination with an ore-smelting chamber, of a combustion chamber or chambers for heating said ore-smelting chamber, means for withdrawing the heated products of combustion and unconsumed gases from said ore-smelting chamber, a carbureter receiving said heated products of combustion and unconsumed gases, superheating-pipes adjacent to said ore-smelting chamber, means for returning said heated products of combustion and unconsumed gases from said carbureter to said superheating-pipes, means for feeding steam to said superheating-pipes, and communications between said superheating-pipes and said combustion chamber or chambers.
5. In a smelting-furnace, the combination with an ore-smelting chamber, of an inclosure communicating with said ore-smelting chamber, a partition in said inclosure dividing the same into a roasting-chamber and a gas-flue, and a removable partition between said roasting-chamber and smelting-chamber.
6. In a smelting-furnace, the combination with an ore-smelting chamber, of an inclined inclosure communicating with said ore-smelting chamber, a partition in said inclosure dividing the same into a roasting-chamber and a gas-flue, and a removable partition between said roasting-chamber and said smelting-chamber.
7. In a smelting-furnace, the combination with an ore-smelting chamber, of an inclosure communicating with said ore-smelting chamber, a grating in said inclosure dividing the same into a roasting-chamber and a gas-flue, and means for discharging the ore from said roasting-chamber into said smelting-chamber.
8. In a smelting-furnace, the combination with an ore-smelting chamber, of an inclined inclosure communicating with said ore-smelting chamber, a grating in said inclosure dividing the same into a roasting-chamber and a gas-flue, and means for discharging the ore from said smelting-chamber.
- from said roasting-chamber into said smelting-chamber.
9. In a smelting-furnace, the combination with an ore-smelting chamber, of a combustion-chamber for heating said ore-smelting chamber, an inclined inclosure communicating with said ore-smelting chamber, a grating in said inclined inclosure dividing the same into an ore-roasting chamber and a gas-flue, and means for discharging the ore from said roasting-chamber into said smelting-chamber.
10. In a smelting-furnace, the combination with an ore-smelting chamber, of an inclosure communicating with said ore-smelting chamber, and a water-grating in said inclosure dividing the same into a roasting-chamber and a gas-flue.
11. In a smelting-furnace, the combination with an ore-smelting chamber, of an inclined inclosure communicating with said ore-smelting chamber, and a water-grating in said inclined inclosure dividing the same into an ore-roasting chamber and a gas-flue.
12. In a smelting-furnace, the combination with an ore-smelting chamber, of an inclined inclosure communicating with said ore-smelting chamber, a grating in said inclosure dividing the same into an ore-roasting chamber and a gas-flue, and a movable grating arranged between said ore-roasting chamber and said ore-smelting chamber.
13. In a smelting-furnace, the combination with an ore-smelting chamber, of an inclined inclosure communicating with said ore-smelting chamber, a water-grating in said inclined inclosure dividing the same into an ore-roasting chamber and a gas-flue, and a movable water-grating arranged between said ore-roasting chamber and said ore-smelting chamber.
14. In a smelting-furnace, the combination with an ore-smelting chamber, of a roasting-chamber communicating with said ore-smelting chamber, a combustion-chamber for heating said ore-smelting chamber, a carbureter, means for withdrawing the heated products of combustion and gases from said ore-roasting chamber and delivering the same to said carbureter, and means for returning said gases and products of combustion to said combustion-chamber.
15. In a smelting-furnace, the combination with an ore-smelting chamber, of a roasting-chamber communicating with said ore-smelting chamber, a combustion-chamber for heating said ore-smelting chamber, a carbureter, means for feeding fuel to said carbureter, means for withdrawing the heated products of combustion and gases from said ore-roasting chamber and delivering the same to said carbureter, and means for returning said gases and products of combustion to said combustion-chamber.
16. In a smelting-furnace, the combination

with an ore-smelting chamber, of a combustion-chamber for heating said smelting-chamber, a fuel-injector for said combustion-chamber, superheating-pipes adjacent to said 5 smelting-chamber, steam-pipe connections for said injectors, passages between said combustion-chambers and said superheating-pipes, and means for withdrawing the heated products of combustion from said smelting-chamber and returning the same through 10 said superheating-pipes to said combustion-chamber.

17. In a smelting-furnace, the combination with a smelting-chamber, of a combustion-chamber for heating said smelting-chamber, a fuel-injector for said combustion-chamber, superheating-pipes arranged adjacent to said 15 smelting-chamber, steam-pipe connections for said fuel-injectors, communications between 20 said combustion-chamber and said superheating-pipes, and connections between said superheating-pipes and said steam-pipe connections.

18. In a smelting-furnace, the combination 25 with an ore-smelting chamber, of superheating-pipes for said chamber, combustion-chambers for said smelting-chamber, passages leading from said superheating-pipes to said combustion-chambers, fuel-injectors for 30 said combustion-chambers, steam-pipe connections for said fuel-injectors, and passages

leading from said steam-pipe connections to said superheating-pipes.

19. In a smelting-furnace, the combination with an ore-smelting chamber, of superheating-pipes for said chamber, combustion-chambers for said smelting-chambers, a passage leading from one end of each of said superheating-pipes to said combustion-chamber, and passages leading from said steam-pipe 40 connections to the other end of said superheating-pipes.

20. In a smelting-furnace, the combination with an ore-smelting chamber, of a plurality of superheating-pipes arranged adjacent to 45 said smelting-chamber and connected to form a continuous passage, a combustion-chamber for said smelting-chamber, fuel-injectors for said combustion-chambers, steam-pipe connections for said fuel-injectors, passages leading from one end of each of said superheating-pipes to one of said combustion-chambers, and passages from said steam-pipe 50 connections to the opposite ends of said superheating-pipes.

In testimony whereof I have hereunto set my hand and affixed my seal in the presence of the two subscribing witnesses.

FREDERICK L. McGAHAN. [L. S.]
